UNITED STATES PATENT OFFICE.

WILLIAM A. RINGLER, OF PHILADELPHIA, PENNSYLVANIA, ASSIGNOR TO GLOBE
WERNICKE CO., OF CINCINNATI, OHIO, A CORPORATION OF OHIO.

DISPLAY DEVICE.

Application filed May 15, 1922. Serial No. 561,066.

To all whom it may concern:

Be it known that I, WILLIAM A. RINGLER, a citizen of the United States, residing at Philadelphia, county of Philadelphia, State 5 of Pennsylvania, have invented a new and useful Display Device, of which the following is a specification.

My present invention comprehends a novel construction of a display device which 10 can be economically manufactured and wherein advertising material or other desired data can be displayed and at the same time can be readily replaced with other matter.

15 It further comprehends a novel construction of a display device comprising a frame or holder and a novel construction and arrangement of a removable member which is formed in a novel manner and provided 20 with a series of superimposed pockets having a backer which contributes to hold in place a transparent cover which prevents the material carried in the pockets from interfering with the removal of the pockets 25 and their backer from the frame.

It further comprehends a novel construction of a display device wherein a sheet of material is folded upon itself to form a series of pockets one of which is adapted 30 to receive a transparent sheet such as, for example, celluloid, while the opposite end of the sheet of material is folded upon itself to form a pocket to receive the opposite end of said transparent sheet of material.

35 Other novel features of construction and advantage will hereinafter more fully appear in the detailed description and the appended claims.

For the purpose of illustrating my invention, I have shown in the accompanying drawings embodiments thereof which are at present preferred by me, since these embodiments will be found in practice to give satisfactory and reliable results. It is, however, to be understood that the various instrumentalities of which my invention consists can be variously arranged and organized and that my invention is not limited to the precise arrangement and organization 45 of these instrumentalities as herein shown and described.

Figure 1 represents a front elevation of a display device, embodying my invention.

Figure 2 represents a top plan view 55 thereof.

Figure 3 represents a section on line 3—3 of Figure 1.

Figure 4 represents, in front elevation, a portion of the holder.

Figure 5 represents a section on line 5—5 60 of Figure 1.

Figure 6 represents, in front elevation, another embodiment of my invention.

Figure 7 represents a section on line 7—7 65 of Figure 6.

Figure 8 represents, in perspective, and in detached position, a type of letter which may be employed.

Figure 9 represents a fragmentary section 70 of the holder before the backing is applied to it.

Figure 10 represents, in rear elevation, a portion of the holder at one stage of the manufacture.

Similar numerals of reference indicate 75 corresponding parts.

Referring to the drawings, 1 designates a frame or support having a front opening 2 and a top opening 3 through which latter the holder 4 can be inserted into position. The 80 holder 4 is formed from a sheet of suitable material which is folded and lapped upon itself, as will be understood from the drawings, and a strip of material 6 having adhesive on one of its faces is then secured to 85 the back of the folded sheet 5 in order to secure it in folded position, it being understood that the fold forms a series of superimposed pockets 7 into which the matter to be displayed is slid.

The free upper end portion of the sheet 5 is bent downwardly to form the flap 8. I preferably apply a sheet of backing material 9 to the back of the sheet 5 and the side portions are bent over to form the marginal 95 edges 10 which are secured to the holes by means of adhesive. The ends of the backing 9 are bent over at the top and bottom and secured by means of adhesive in any desired manner to the marginal edge portions 10 100 thereby forming a laterally extending stiffening portion 11 which is secured by adhesive or other means to the flap 8, as shown at the top of Figure 4, and the bottom portion is formed in a similar manner as will 105 be apparent from the foregoing description.

12 designates a sheet of transparent material such as, for example, celluloid, which preferably is of such width that it will cover the front face of all the pockets and the side 110

marginal edges 10 except at its free end where it is cut away to form shoulders 13 thereby forming a tongue 14 which at the top is slipped into the pocket 15 formed by the flap 8 and at the bottom it is slipped into the lowermost pocket 7.

16 designates an indicator consisting of a strip of material deflected upon itself to form a tongue 17 which is adapted to be received in one of the pockets 7, see Figure 9, and the front face of the indicator is adapted to have indicated thereon a desired letter such as, for example, that shown at 18 or any other desired insignia or display matter.

19 designates a card illustrating another type of display matter which can be inserted in a pocket 7.

If it is desired to stiffen the holder the backer 9 can be formed of sheet metal or of other material of a less flexible nature than paper or card-board and in Figures 6 and 7 the construction is the same as that already described except that the backer 20 is formed of sheet metal, the free ends of which are deflected over at the top and bottom as at 21 in order to form a pocket to receive the tongue 15 of the transparent cover 12 and the sides of the backer are deflected over the front edges of the pocket forming sheet 5, as indicated at 22, and these at their ends are pressed down against the flap 21. When it is desired to remove the holder to change the matter displayed, all that it is necessary to do is to press upwardly with the thumb or finger on the transparent cover 12 and the holder 4 will be removed as a unit of structure from the frame. The transparent sheet 12 is then removed and the display matter changed as may be desired.

It will be apparent that when the holder is removed from the frame the transparent cover 12 will prevent the display matter from catching against the portion 23 of the frame, see Figure 1, so that the holder can at all times desired be readily and quickly withdrawn from the frame. The transparent cover 12 carried by the holder 4 serves to protect the holder and the display matter so that dust and foreign material will not collect in the pockets or on the display matter.

It will now be apparent that I have devised a new and useful display device which embodies the features of advantage enumerated as desirable in the statement of the invention and the above description, and while I have, in the present instance, shown and described embodiments thereof which will give in practice satisfactory and reliable results, it is to be understood that such embodiments are susceptible of modification in various particulars without departing from the spirit or scope of the invention or sacrificing any of its advantages.

Having thus described my invention, what I claim as new and desire to secure by Letters Patent, is:

1. A display device, comprising a frame having a sight opening, and an opening in one of its walls and a display holder removably carried by the frame, and insertible and removable through said wall opening, said display holder being formed from a sheet of material lapped upon itself to form a series of pockets to receive the matter to be displayed and having its upper portion deflected upon itself to form a cover receiving pocket, and a transparent cover having one end inserted into said cover receiving pocket, whereby when the display holder is withdrawn from said frame the display matter carried by the holder will not catch on a wall of said sight opening. 85

2. A display device, comprising a frame having a sight opening, and an opening in one of its walls and a display holder removably carried by the frame, and insertible and removable through said wall opening, said display holder being formed from a sheet of material lapped upon itself to form a series of pockets to receive the matter to be displayed and having its upper portion deflected upon itself to form a cover receiving pocket, and a transparent cover having its lower end inserted in a pocket and its upper end inserted into said cover receiving pocket, whereby when the display holder is withdrawn from said frame the display matter carried by the holder will not catch on a wall of said sight opening. 95 100

WILLIAM A. RINGLER.
